UNITED STATES PATENT OFFICE

159,959

WRINGER

Fred A. Conterman, deceased, late of Jamestown,
N. Y., by Janet L. Conterman, administratrix,
Jamestown, N. Y., assignor to Blackstone Cor-
poration, Jamestown, N. Y., a corporation of
New York

Application September 17, 1948, Serial No. 148,642

Term of patent 7 years

(Cl. D49—1)

To all whom it may concern:

Be it known that Fred A. Conterman (deceased), late a resident of Jamestown, New York, and a citizen of the United States, invented a new, original, and ornamental Design for a Wringer, of which the following is a specification, reference being had to the accompanying drawing, forming part thereof, and in which

Fig. 1 is a front elevational view of a wringer showing the new design of Fred A. Conterman, deceased;

Fig. 2 is a top plan view;

Fig. 3 is an end elevational view.

What is claimed is:

The ornamental design for a wringer, substantially as shown.

JANET L. CONTERMAN,

*Administratrix of the Estate of Fred A. Conter-
man, Deceased.*
